UNITED STATES PATENT OFFICE.

RAYMOND H. BAUR, OF KENILWORTH, DISTRICT OF COLUMBIA.

ENGINE VALVE.

Application filed March 26, 1921. Serial No. 455,762.

To all whom it may concern:

Be it known that I, RAYMOND H. BAUR, a citizen of the United States, residing at Kenilworth, in the District of Columbia, have invented certain new and useful Improvements in Engine Valves, of which the following is a specification, reference being had therein to the accompanying drawing.

This invention relates to certain new and useful improvements in engine valves and pertains more particularly to the type commonly employed in connection with internal combustion engines and known as puppet valves.

15 The principal object of the present invention is to provide a valve structure in which a relative movement between the valve disk and its seat is accomplished for the purpose of preventing carbon or other deposits from accumulating between these parts. It is acknowledged by those skilled in this particular art that carbon deposits between the valve face and its seat not only prevent the proper closing of the valve, but in course 20 of time will pit the valve face or its seat to such an extent that they are beyond the point of repair, thereby requiring the complete change of these parts. The present invention, therefore, aims to prevent accumulations of any foreign substances, such as 25 carbon, etc., by causing a slight or positive rotative movement to the valve stem just as the same is seating, thereby grinding or reducing any interposed matter.

30 Another object of the invention resides in the novel manner of imparting the oscillatory movement to the valve stem, which, in this case, is of gradual acting character during the unseating of the valve, but abrupt 35 during the seating action thereof. This is desirable for the fact that the relative movements between the valve seat and the face of the valve is required to be assured just as the valve is entering or closing upon its seat.

40 A further object of the invention is to provide a locking key, which not only retains the spring abutment in place on the valve stem, but also constitutes an active part of the mechanism for transmitting the 45 desired motion to the valve stem during the reciprocations thereof.

A still further aim of the present invention resides in the manner of housing or enclosing the valve stem and the mechanism 50 mounted therein within a bushing or sleeve, which not only prevents, to a certain extent,

accumulations of dust and dirt thereon, but also acts as a shield to avoid malicious tampering with the enclosed parts.

While in the foregoing there has been set forth some of the advantages gained by the use of the invention, it is, of course, understood that others will readily suggest themselves to mechanics skilled in this particular art when reading the following specification in connection with the attached drawings. In the drawings there is shown the preferred embodiment of the invention, but they should be considered only as illustrative of the attachment and not in a limiting sense, as certain variations may be resorted to without sacrificing any of the spirit of the invention.

Similar letters of reference indicate like parts in the drawings, in which:—

75 Figure 1 is a transverse section taken through an engine cylinder and showing the attachment in position on the valve stem.

Figure 2 is a detail sectional view of the attachment taken at right angles to the illustration shown in Figure 1.

Figure 3 is a perspective view of the locking key.

Figure 4 is a transverse section taken on line 4—4 of Figure 2.

Figure 5 is a perspective view of the locking member which is adapted to coact with the cross key.

Figure 6 is a modified perspective view of the spring abutment.

Considering the drawings more in detail, there is shown at 1 an engine cylinder having attached to the side walls thereof the valve casings 2 which are in turn provided with valve seats 3. Within the cylinder 1 is arranged the piston 4 and covering the upper end of the cylinder is a removable plate designated 5. This plate 5 is detachably secured to the engine by securing bolts 6. For the purpose of better illustrating 95 my invention, there is shown inlet and exhaust conduits designated 7 and 8, respectively, which in turn communicate with oppositely disposed valve casings 2—2, as shown in the drawings. These valve casings 2—2 are angularly arranged on the side walls of the engine or cylinder 1, which has been found to work to an advantage in uniformly distributing the heat to the exposed ends of the valve disks. This arrangement 100 also permits the use of a relatively shallow cover plate as shown in the drawings, which

when detached from the engine completely exposes the entire upper area of the cylinder and the valve casings. It is, of course, understood that the attachment may be employed on any standard type of valve now on the market, whether the same be in an overhead or L-type of engine valves.

Slidably arranged within each casing 2 is a valve stem 9 having at one end thereof a head or disk 10 which is adapted to coact with the valve seat 3 in the casing 2. Through a suitable aperture in the valve stem and projecting beyond the sides thereof is arranged a cross key designated 11. This cross key has a central enlarged portion 12 which is adapted to conform with the cross area of the valve stem 9. Arranged upon the valve stem and above the cross key 11 is a locking member designated 13. This locking member is provided with oppositely disposed slotted portions 14 which are adapted to register or interlock with the cross key 12. Positioned above the locking member 13 and frictionally resting thereagainst is a spring abutment designated 15, between which and the under face of the casing is interposed a coiled spring 16. This spring 16 tends to force the valve to its proper seat when the valve is relieved from its positive or mechanical lifting member.

Secured to the under face of the valve casing 2 in any suitable manner is a bushing or sleeve member indicated at 17. This sleeve member acts as a housing or casing 35 to the mechanism mounted on the valve stem and therefore prevents accumulations of dust or any other foreign matter on said mechanism. This bushing or sleeve 17 is provided with oppositely disposed slotted portions as indicated at 18, one side wall 40 of this slot being of gradual tapering formation as at 19, while the opposite wall has a straightened portion indicated at 20 and an abrupt curve as at 21.

The extended portions of the cross key 11 are reduced as shown at 22, upon which a bushing 23 is mounted for the purpose of rotatably supporting rollers or sleeves 24. The sleeves as well as the bushings are maintained in position on the reduced arm 22 of the cross key 11 by a washer 25 secured in position by a cross key 26 entering an aperture 27 in the ends of the key.

As shown in Fig. 6 of the drawings the spring abutment 15' may be provided with oppositely extending slotted portions 28-28 in the base thereof for the purpose of interlocking with the cross key 11. When this form of abutment is used the locking member 13 is eliminated from the structure.

In operation the device will function as follows:

When the tappet, or other mechanical means, exerts its lifting action upon the valve stem 9, the rollers or sleeves 24, which

are secured to the extended portions of the cross key 11, will ride within the slotted portions 18 and against the gradually tapering wall 19 and thereby effectively move the valve stem in one direction about its longitudinal axis. The torsional action of the spring, incidental to the reciprocatory movements of the valve has little or no effect upon oscillating the valve stem. This is accomplished in the present case by loosely mounting the abutment 15 on top of the locking member 13 which permits the member 15 to have a relative rotary movement about the valve stem. On the return stroke of the valve, due to the action of the expansive 80 spring 16, the rollers or sleeves 24 will not contact with the opposite side wall of the slotted portion 18 until they are adjacent their lowest point of travel, at which instance they will engage the abrupt curved 85 portion 21 and thereby transmit to the valve stem a relatively rapid rotative impulse just as the valve is coming to its seat.

The invention as a whole is one consisting of a minimum number of parts which are easily attached or detached to or from the valve without the requirement of a skilled mechanic and which maintains the effective part of the valve always in its highest state of efficiency, and thereby permits the successful operation of the engine.

What I desire to claim by U. S. Letters Patent is:

1. A valve of the character described, the combination of a valve chamber having a seat therein, a reciprocatory valve stem having a disk on one end thereof adapted to coact with said seat, and means for positively imparting a gradual rotative movement to said stem during one of its reciprocatory movements, and a more rapid rotation thereof in the opposite direction during its opposite reciprocatory movement.

2. A valve of the character described, the combination of a valve chamber having a seat therein, a reciprocatory valve stem having a disk on one end thereof adapted to coact with said seat, and means for positively imparting a gradual rotative movement to said stem during its lifting action 110 and a more rapid rotation thereto in the opposite direction during its seating action.

3. A valve of the character described, the combination of a valve casing having a seat therein, a valve stem provided with a disk at one end thereof adapted for coaction with said seat, a cross key affixed to said valve stem, an abutment keyed to said cross key, a spring interposed between said abutment and the valve casing for forcing the valve disk upon the seat, and means coacting with the ends of the cross key for positively imparting a gradual axial rotative movement to said stem during one of the reciprocations thereof and a 130

more rapid rotative movement to the valve stem in the opposite direction during the opposite reciprocatory movement.

4. A valve of the character described, the combination of a valve casing having a seat therein, a valve stem provided with a disk at one end thereof, adapted to contact with said seat, a member affixed to the valve stem and having oppositely extending portions, a spring surrounding the valve stem and interposed between said affixed member and the valve casing, a bushing surrounding the spring and provided with means coactive with the extended ends of the affixed member for imparting a gradual rotative movement in one direction to the valve stem during one of its reciprocatory movements and a more rapid rotation thereof in the opposite direction during the opposite reciprocatory movements.

5. A valve of the character described, the

combination of a valve casing having a seat therein, a valve stem provided with a disk at one end thereof adapted to coact with said seat, a member affixed to the valve stem and having oppositely extending portions, a spring surrounding the valve stem and interposed between said affixed member and the valve casing, a bushing enclosing the spring and provided with oppositely directed slots therein for the reception of the extended ends of the affixed member whereby oscillatory motion is transmitted to the valve stem during the reciprocations thereof, one wall of the slot having a gradual curve throughout the length thereof and the opposite wall of the slot having an abrupt curve adjacent one end thereof.

In testimony whereof I hereunto affix my signature.

RAYMOND H. BAUR.
